TANK LINER CONSTRUCTION

Neil C. Stillwell, P.O. Box 752, Kokomo, Ind.
Original application June 5, 1962, Ser. No. 200,216, now Patent No. 3,190,663. Divided and this application Oct. 30, 1964, Ser. No. 407,674
4 Claims. (Cl. 220—63)

This is a division of my application, Serial No. 200,216 filed June 5, 1962, now U.S. Patent No. 3,190,663.

This invention relates generally to a tank liner, and more specifically to a tank liner having an integral construction by which a fluid-tight static seal may be effected between it and associated hardware.

A particularly useful application is made between a flexible plastic liner of a tank and the plumbing or other hardware connected thereto. Where a plastic liner is employed in a tank, its purpose is to protect the interior of the tank from exposure to the fluid contents. Although the bag liner may be tight, a problem arises in establishing a fluid-tight connection between the plastic liner and plumbing leading thereto, it being necessary that the seal construction be such that there can be no possible leakage through the seal into the interior of the tank, between the interior wall of the tank and the exterior wall of the liner. In particular, it is necessary to have a connection which can be freely disassembled and reassembled whenever the occasion warrants using only ordinary hand tools to do so. The liner may be employed by the purchaser in any one of several different tanks, and therefore the construction disclosed herein preferably is provided in more than one location, thereby enabling universality of use of such liner.

The present invention contemplates the provision of a tank liner having a series of concentric formations in the plastic material of which the liner is made, such annular or ring formations surrounding the opening which is to be provided with the fitting. By such structure, I have found that whereas one out of five previous seals were susceptible to leakage, no leakage has been found in a large number of connections made in accordance with the principles of this invention.

Accordingly, it is an object of the present invention to provide a tank liner in which there is embodied integrally a static seal.

Another object of the present invention is to provide a static seal for a plastic tank-liner, which seal may be freely assembled and disassembled by means of ordinary hand tools.

Yet another object of the present invention is to provide a liner seal-construction which at the outset is optionally usable.

Many other advantages, features and additional objects of the present invention will become manifest to those versed in the art upon making reference to the detailed description and the accompanying sheets of drawings in which preferred structural embodiments incorporating the principles of the present invention are shown by way of illustrative example.

On the drawings

FIG. 1 is an enlarged cross-sectional view taken through the seal portion of a tank liner provided in accordance with the principles of the present invention;

FIG. 2 is a plan view of the plastic portion of the seal shown in FIG. 1 prior to assembly;

FIG. 3 is a fragmentary cross-sectional view taken along line III—III of FIG. 2 when the same is distorted;

FIG. 3a is a fragmentary cross-sectional view of a further embodiment of my invention, taken similarly to FIG. 3, but illustrated in its free state;

2

FIGS. 4 and 5 are modifications of the construction shown in FIG. 1;

FIGS. 6 and 7 are modifications of the structure shown in FIG. 2; and

FIGS. 8 and 9 comprise diagrammatic representations of structure for forming the construction of FIG. 2.

As shown on the drawings

The principles of this invention are particularly useful when embodied in a tank liner having a static seal construction such as illustrated in FIG. 1, generally indicated by the numeral 10. In this embodiment, the tank liner includes a first layer 11 of plastic and a second layer 12 of plastic having an aperture receiving a rubber grommet 13. The grommet 13 is carried on the outer diameter of an annular fitting 14 having a rigid flange 15. A nut 16 acting through a rigid washer 17 serves to clamp the annular grommet 13 against the plastic layers 11 and 12.

As brought out below, the wall of the tank liner may comprise a single thickness of elastic thermoplastic material, such as vinyl plastic, but in FIG. 1, such wall is illustrated as comprising two plastic layers 11, 12, each of which is elastic heat-sealable material of thin section, the thickness of which has been exaggerated in the drawing for clarity. For example, where vinyl plastic layers are employed, each of a pair may be about .016 inch in thickness. Such plastic material is not only elastic but is heat sealable.

The layers 11 and 12 may be coextensive so that the same may comprise a double thickness bag or liner. In certain instances, a single thickness 11 is sufficient, and in such instances, if it is desired to employ two layers at the seal, the plastic layer 12 comprises a disk secured to the layer 11 as described in detail below.

In FIG. 2, there is shown a plan view of the plastic layers 11, 12 as seen in FIG. 1 prior to assembly. This structure comprises a layer 12 which is a disk or patch secured by a series of radially spaced heat seals 18-22 which are substantially concentric with each other and which have a relatively large radial extent as compared to their radial spacing. At manufacture, a central opening 23 may be omitted so that the tank liner material 11 may have a number of heat seals 18-22 disposed at various points thereon for selective use depending upon the structure with which the same is to be associated. Where the aperture 23 has been temporarily omitted, the presence of the layer 12 is in no way harmful. However, when it is desired to make a fluid-tight connection with the liner having the layer 11, the central portion is cut out as at 23 to provide such aperture which surrounds the grommet 13. In a typical embodiment, the heat seal 18 should be made to have an outside diameter of three-quarters inch with the successive heat seals 19-22 ranging in size up to 1 1/4" diameter.

Each of the heat seals 18-22 comprises a reduced thickness zone of altered resistance to stretching connected by annular connecting portions or rings of increased thickness between such heat-sealed zones, which connecting portions have an oppositely altered resistance to stretching. It is believed that this difference in resistance to stretching comes about as schematically illustrated in FIG. 3.

FIG. 3 represents a radial cross-section of the structure shown in FIG. 2, but distorted at its center as if by receiving a grommet or fitting having an external size greater than the size of the aperture. Thus, each of the heat seals or connecting rings acts much like a rubber band which is under tension, or like a garter, and tends to draw the aperture to a smaller size. This radially inward force is sufficiently great so that when a clamping

force is applied to the grommet 13, the plastic layer 11 does not extrude outwardly and is entirely leak resistant at the fitting.

I have found that there is no particular form of grommet necessary to practice the instant invention. By way of example, there is illustrated in FIG. 4 a grommet 24 which has an external profile similar to a standard O-ring, but with a peripheral outwardly opening groove receiving the plastic layers 11 and 12.

Further, the use of a grommet per se is not absolutely essential and an equivalent structure is shown in FIG. 5 wherein the grommets 13 and 24 have been replaced by a pair of O-rings 25, 26, the plastic layer 11 directly engaging the peripheral surface of the fitting 14, and the O-ring 26 being optional.

In FIG. 1, the bottom of the groove in the grommet 13 has a diameter larger than the free diameter of the aperture in the plastic layers 11 and 12 of the tank liner. A similar relationship applies to the grommet of FIG. 4. Similarly, the outside diameter of the fitting 14 is greater than the free size of the aperture in the plastic layers 11, 12 in FIG. 5. In FIGS. 1 and 4, the plastic serves to draw the rubber grommets radially inwardly to compress them against the fitting 14, while in FIG. 5, the plastic directly engages the fitting 14. In all forms, the clamping member 16, illustrated for convenience as being a nut, creates a seal between the plastic and the rubber and the plastic does not extrude radially outwardly, due to the concentric heat seal rings or bonds or heat-formed formations. If desired, a number of annular rings 15c may be provided integral with the flange 15 to further minimize the likelihood of radial extrusion of the grommet 13.

In FIG. 6, there is illustrated a variation of the structure shown in FIG. 2 wherein the heat seals are oval-shaped for use as on a removable tank-closing plate which is removable such as for inspection or other reasons necessitating internal access within the tank liner. The length of the major diameter of such plate may comprise several inches.

In FIG. 7 there is illustrated a further variation of the structure shown in FIG. 2 which includes the layers 11 and 12 described before, having the heat seal 22. However, associated therewith, there is a series of interrupted heat seals 27-30, each comprising a number of arcs, and wherein the arcs of adjacent rows may be staggered as illustrated. In the event that the elastic material employed has too great a resistance to stretching with a heat-seal pattern such as shown in FIG. 2, the pattern shown in FIG. 7 may be employed so that each successive heat-seal or heat-formed formation gives slightly less tension. However, it is preferred that there be one continuous heat seal or formation 22 to preclude any fluid leakage between the layers 11 and 12 or outwardly from the central opening.

The heat seals, rings, or bonds thus far described comprise successive rings which are alternately thicker and thinner in thickness. Ordinarily, each thermoplastic bond comprises an annular area of reduced thickness. The material originally present at such areas flows radially, during heat sealing or forming, to the connecting portions, which thus ordinarily grow slightly in thickness in an axial direction due to reception of plastically flowing material.

This type of structure may be provided on opposite faces of each illustrated and described seal, each of which may comprise a single thickness of plastic material, both such features being shown in FIG. 3a. Where a single layer of thermoplastic material is employed at the tank liner seal, each "heat seal" or ring has all the properties described above, except that it does not bond together two layers of material. However, the term "heat seal" has been employed to reflect the physical properties obtained by such method of manufacture.

In FIG. 3a, a sheet of material 35, again comprising

an integral part of the tank liner, and shown in exaggerated thickness, is provided with a series of concentric double-faced "heat seals" or rings 36-40 spaced from each other by a series of connecting rings 41-45 of a thickness greater than the sheet 35. In this form, the cross-sectional area from each seal 36-40 to the adjacent connecting rings 41-45 changes, and therefore the yieldability of successive elements varies, as does the yieldability of successive rings 41-45.

The heat-formed rings 36-40 successively have an increasing radial length as well as an increasing resultant thickness, while the heat-formed rings 41-45 successively have an oppositely changing or decreasing radial cross-sectional area.

In FIG. 8 there is illustrated diagrammatically a structure such as may be employed to provide the heat-seal pattern of FIG. 2. The plastic layers 11 and 12 are disposed between electrodes 31, 32 connected to a suitable source of high frequency current 33. The electrode 32 includes a number of concentric rings having an arrangement corresponding to the pattern of FIG. 2, or more generally, having an arrangement corresponding to the pattern desired to be produced in the tank liner. By use of an additional electrode 32 in place of the electrode 31, dual treated faces may be provided as shown in FIG. 3a. A variation in the structure of the electrode 32 is shown in FIG. 9 and is generally indicated at 34. Slotting of certain rings produces a selected amount of pattern interruptions and staggering of the type illustrated in FIG. 7.

By providing a relatively large number of concentric rings or heat seals 18-22 as illustrated in FIG. 2, the resulting structure can be cut to various sizes to accommodate various size fittings. However, it is preferred that a plurality of annular rings or heat seals be left intact to perform as described herein. A number of fittings such as 14 may be used at different locations, and two or more can be joined to form a unitary fitting having a plurality of portions corresponding to that illustrated at

40 FIG. 14. Although various minor modifications might be suggested by those versed in the art, it should be understood that I wish to embody within the scope of the patent warranted hereon all such embodiments as reasonably and properly come within the scope of my contribution to the art.

I claim as my invention:

1. A liner for a tank, comprising:

(a) a bag of elastic thermoplastic sheet material having means providing an aperture therethrough; and
(b) said means extending concentrically about and adjacent to said aperture and consisting of an annular formation in said sheet material integral with said bag only at the radially outermost edge of said formation along a line consisting of the outer periphery of said formation, said annular formation having a radial cross-section varying in thickness from that of said sheet material, and being radially elastic at said aperture with a radial elasticity varying from that of said sheet material remote from said formation.

2. A liner for a tank, comprising:

(a) a bag of elastic thermoplastic sheet material having means providing an aperture therethrough; and
(b) said means comprising a series of several radially spaced and radially joined elastic ring formations in said sheet material, said series being integral with said bag only at the radially outermost edge of the radially outermost one of said series of ring formations along a line consisting of the outer periphery of said series, each of said ring formations having a greater cross-sectional radial extent than its radial spacing from adjacent ring formations, and said ring formations extending about and adjacent to said aperture in substantially concentric relation to each other.

3. A liner for a tank, comprising:

- (a) a bag of elastic thermoplastic sheet material having means providing an aperture therethrough receptive of a fluid-flow fitting; and
- (b) said means comprising a series of several radially spaced and radially joined elastic ring formations in said sheet material, said series being integral with said bag only at the radially outermost edge of the radially outermost one of said series of ring formations along a line consisting of the outer periphery of said series, each of said ring formations having a greater cross-sectional radial extent than its radial spacing from adjacent ring formations, and said ring formations extending about and adjacent to said aperture in substantially concentric relation to each other, said ring formations extending about said aperture as ovals for acting elastically in a radially inward direction on the fitting to form a liquid-tight seal between the bag and the fitting.

4. A liner for a tank, comprising:

- (a) a bag of elastic thermoplastic sheet material having means providing an aperture therethrough receptive of an oval tank closure; and
- (b) said means comprising a series of several radially spaced and radially joined elastic ring formations in said sheet material, said series being integral with

said bag only at the radially outermost edge of the radially outermost one of said series of ring formations along a line consisting of the outer periphery of said series, each of said ring formations having a greater cross-sectional radial extent than its radial spacing from adjacent ring formations, and said ring formations extending about and adjacent to said aperture in substantially concentric relation to each other, said ring formations extending about said aperture as ovals for acting elastically in a radially inward direction on the tank closure to form a liquid-tight seal between the bag and the tank closure.
